UNITED STATES PATENT OFFICE.

THOMAS J. WALLACE, OF ALBANY, VERMONT.

STANCHION.

SPECIFICATION forming part of Letters Patent No. 770,203, dated September 13, 1904.

Application filed March 5, 1904. Serial No. 196,696. (No model.)

To all whom it may concern:

Be it known that I, THOMAS J. WALLACE, a citizen of the United States, residing at Albany, in the county of Orleans and State of Vermont, have invented a new and useful Stanchion, of which the following is a specification.

This invention relates to cattle-stanchions, and has for its object to simplify and improve the construction and produce a device of this character which when in open position will be locked from rotation and when in operative position will rotate to permit a greater freedom to the movements of the animals' heads.

With these and other objects in view, which will appear as the nature of the invention is better understood, the same consists in certain novel features of construction, as herein-after fully described and claimed.

In the accompanying drawings, forming a part of this specification and in which corresponding parts are denoted by like designating characters, is illustrated the preferred form of the embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages, and the right is therefore reserved of making all the changes and modifications which fairly fall within the scope of the invention and the claims made therefor.

In the drawings thus employed, Figure 1 is a perspective view of one of the improved stanchions in its closed or operative condition. Fig. 2 is a similar view with the improved device in its open or inoperative position. Fig. 3 is an enlarged sectional detail of the upper portion of the device.

The improved stanchion construction will be supported in a suitable framework, as represented, and erected in a stable, shed, or other suitable locality and comprising in its organization spaced base and head timbers 10 11, connected at suitable intervals by vertical members 12 with the improved stanchions disposed in the panel-like openings between them.

The improved stanchions consist of a base member 13 and head member 14, connected at one end by a stationary bar 15, the base and head members pivoted at 16 17, respectively, in the base and head timbers 10 11, as shown. 55 The head member 14 is provided with a longitudinal slot 18, in which the free end of a movable arm 19 swings, the movable arm being pivoted at 20 in the base member 13. Immediately pivoted at 21 in the slot 18 above the free end of the swinging bar 19 is a locking-lever 22, having a recess 23 in its longer end for engagement with the free end of the swinging bar 19 and with a lug 24 projecting from its shorter end above the upper line of 65 the member 14 when the lever is engaged with the swinging bar, the projecting lug providing means whereby the shorter end of the lever may be tilted to release the longer end from the swinging bar. The member 14 is 70 also provided with a transverse stop 25 to limit the outward movement of the swinging bar. Attached to the head-timber is a U-shaped keeper 26, between whose spaced sides the shorter end of the lever 22 will pass when 75 released from the swinging member 19.

In operating the device when it is desired to set the stanchions to receive the cattle the shorter end of the locking-lever 22 is depressed by bearing down upon the lug 24, which elevates the longer end and releases the swinging bar 19, which falls outward by gravity until it rests against the end stop 25, while at the same time the longer end of the locking-lever has fallen by gravity and moved the 85 shorter end into the space between the sides of the keeper member 26, thereby automatically locking the rotative stanchion within its supporting-framework. When the necks of the cattle are in position between the bars, 90 the bar 19 is moved over into operative position, carrying the locking-lever with it and causing it to automatically engage therewith. This action releases the shorter end of the locking-lever from the keeper 26 and permits 95 the stanchion to swing upon its pivots 16 17. By this simple means the stanchions are supported from rotation when not in use and in proper position to receive the cattle and are released automatically by the action of secur- 100

ing the cattle and permitted thereafter to rotate with the movements of the animal's head. The animal will be secured in the stanchion, but under less restraint than with stationary 5 stanchions.

The parts will preferably be of wood, with metal pivot members, and can be cheaply constructed and will not require the use of springs or other similar attachments, which are liable 10 to get out of order.

Any required number of the improved stanchions may be employed in the supporting-framework and arranged in any desired relative position.

15 Having thus described the invention, what is claimed is—

1. In a device of the class described, the combination with a frame, of a stanchion movably supported thereon and having a movable 20 member, and means carried by the stanchion for engagement with the movable member to lock the same and capable of automatically moving into position for engagement with the frame to lock the stanchion against movement 25 when said means is disengaged from the movable member and the stanchion is in alignment with the frame.

2. In a device of the class described, the combination with a frame, of a stanchion movably supported thereon and having a movable member, and a pivotal locking device carried by the stanchion for engagement with the movable member to lock the same and capable of gravitating into position for engagement 35 with the frame to lock the stanchion against movement when released from the movable member of the stanchion and the stanchion is in alignment with the frame.

3. In a device of the class described, the combination with a frame, of a stanchion movably supported thereon and having a movable member, and a locking device pivoted at one side of its center upon the stanchion with one end formed for engagement with the movable 45 member to lock the same, said locking device

capable of gravitating into an upright position when disengaged from the movable member of the stanchion with its shorter end projected above the stanchion in position for engagement with the frame to lock the stanchion therewith when said stanchion is in alignment with the frame. 50

4. In a device of the class described, the combination with a frame, of a stanchion movably supported thereon and having a movable member, and a locking device pivoted at one side of its center upon the stanchion with its longer end formed for engagement with the movable member to lock the same and capable of gravitating into an upright position with 60 its shorter end projected above the top of the stanchion into position for engagement with the frame to lock the stanchion when the latter is in alignment with said frame.

5. In a device of the class described, the combination with a frame, of a stanchion including a slotted head and a base rotatably connected to the frame, a stationary bar connecting said members, a movable bar pivoted to the base member with its upper end working in a slot in the head member, a locking device pivoted intermediately within the slot of the head member with one end heavier than the other and formed for engagement with the pivotal member of the stanchion in a transverse disposition to lock said member and capable of gravitating into an upright position when released from said member, and a keeper carried by the upper portion of the frame in position to receive the upper end of the locking device when released from the pivotal stanchion member to lock the stanchion against rotation upon the frame. 75

In testimony that I claim the foregoing as my own I have hereto affixed my signature in 80 the presence of two witnesses.

THOMAS J. WALLACE.
